UNITED STATES PATENT OFFICE.

ALEXANDER C. HOWE, OF IDANA, KANSAS.

BUTTER-TUB.

SPECIFICATION forming part of Letters Patent No. 380,487, dated April 3, 1888.

Application filed January 5, 1888. Serial No. 259,883. (No model.)

To all whom it may concern:

Be it known that I, ALEXANDER C. HOWE, of 5
Idana, in the county of Clay and State of
Kansas, have invented a new and Improved
Butter-Tub, of which the following is a speci-
fication, reference being had to the annexed
drawings, forming a part thereof, in which—

Figure 1 is a perspective view of my im-
proved butter-tub, and Fig. 2 is a sectional
10 view of the upper part of the tub.

Similar letters of reference indicate corre-
sponding parts in both views.

The object of my invention is to provide a
butter-tub having an air-tight cover provided
15 with simple and effective fasteners.

The invention consists in the peculiar con-
struction and arrangement of parts, as here-
inafter fully described, and pointed out in the
claims.

20 The chine A of the tub B is grooved or made
in two diameters, *a* *b*, and is flared outwardly
to receive the beveled rabbeted edge *c* of the
cover C. The beveled edge of the cover is ar-
ranged to fit tightly in the grooved chine of
25 the tub, so that when it is pressed down into
place it will be practically air-tight.

To three or more points on the periphery

of the tub are fastened right-angled clips D,
which extend over the top of the chine, and
to the top of the cover C are pivoted latches 30
d, having beveled ends *e*, which are adapted to
wedge underneath the ends of the clips D,
thus forcing the cover downward into the
chine and holding it securely in its place.

The clips D and the latches *d* are preferably 35
made of malleable iron, and to prevent them
from oxidation they are tinned or galvanized.

Having thus described my invention, I claim
as new and desire to secure by Letters Patent—

1. The combination, with the tub B, having 40
a flaring chine A, grooved in two diameters,
a and *b*, of the cover C, having a beveled rab-
beted edge, substantially as described.

2. The combination, with the tub B, having
the flaring chine A, grooved in two diameters, 45
a and *b*, of the cover C, having the flaring
beveled rabbeted edge, the clips D, secured to
the tub, and the beveled latches *d*, adapted to
engage the said clips and hold the cover C se-
curely in its place, substantially as described. 50

A. C. HOWE.
